UNITED STATES PATENT OFFICE.

WARREN L. GREEN, OF NEW YORK, N. Y.

PRINTING-MACHINE.

No. 917,861.

Specification of Letters Patent.

Patented April 13, 1909.

Application filed February 9, 1907. Serial No. 356,603.

To all whom it may concern.

Be it known that I, WARREN L. GREEN, a citizen of the United States, residing in the borough of Manhattan, in the city, county, and State of New York, have invented certain new and useful Improvements in Printing-Machines, of which the following is a specification, reference being had therein to the accompanying drawings, which form a part thereof.

My invention relates to printing machines and more particularly to a type thereof adapted for under-surface printing or printing from intaglio plates.

The main object of the invention is to provide a printing machine which will be capable of printing from intaglio or engraved plates on a continuous web of paper and by a substantially continuous operation, without lowering the quality of the work, thus insuring a machine of large capacity.

A further object is to provide a printing machine employing a plate or form cylinder and a wiping and polishing mechanism in connection therewith consisting of a continuously changing absorbent material whereby all the ink deposited on the surface of the plate or plates, as distinguished from that in the depressions, will be removed and the said surface will be wiped and polished with each rotation of the cylinder and prior to the taking of each impression or imprint therefrom.

A still further object is to provide a wiping and polishing mechanism whereby a fresh section of an absorbent wiping and polishing strip will be automatically fed relative to the form cylinder during each rotation thereof, thus avoiding the necessity for the use of successive wiping and polishing means, and those delays incidental to the removal and substitution of wipers and polishers as such become soiled through continued use to an extent to fail to properly clean and polish the surface of the plate or plates.

A still further object is to provide a wiping and polishing mechanism wherein the wiper will have during the rotation of the form cylinder, movement opposite to the direction of the peripheral travel of said cylinder and a simultaneous lateral movement to insure the utilization of a perfectly clean wiper for the final polishing, and to avoid any tendency of the texture

of the wiper causing a streaking of the surface of the plate or plates.

A still further object is to provide a wiping and polishing mechanism which will be capable of such adjustment and regulation as to permit the wiper to be so tensioned with relation to the form cylinder as to insure that pressure required to properly wipe and polish the plate or plates.

A still further object is to provide a wiping and polishing mechanism capable of using a continuous strip of wiping and polishing cloth and of so rewinding the same after it has passed through the machine as to permit it to be used a second time with the reverse side next the plate or plates.

A still further object is to provide a wiping and polishing mechanism wherein the cloth will be relieved in great part from the strains incidental to feeding it through the machine.

A still further object is to provide a flexible backing for the wiping and polishing cloth so arranged as to facilitate the threading of the cloth through the machine.

A still further object is to provide a machine of this character wherein the D-roll or platen cylinder, will be so driven relative to the plate or form cylinder as to cause it to accurately register with the plate or plates with each successive rotation of the form cylinder.

A still further object is to provide in a machine of this character, a D-roll which, while adapted to be driven through frictional engagement with the plate or plates, will be brought to rest at the end of each rotation in a manner to avoid its overrunning the position necessary to secure a perfect registering thereof with the plate or plates upon the next rotation, and will be capable of being positively started in such synchronism with the movement of the form cylinder or plates, as to insure such registering with each rotation.

A still further object is to provide, in such a machine, means whereby the D-roll or platen cylinder may be thrown in and out of gear as desired in running the machine.

A still further object is to provide in such a machine, means whereby, when the D-roll is out of gear, said roll will be held against any movement through friction between any part of said roll and moving parts of the mechanism adapted to rotate same.

A still further object is to provide a machine wherein any slack in the blanket will be immediately taken up, thus avoiding such looseness or wrinkling of the blanket as 5 would interfere with the frictional drive of the D-roll from the form or plate cylinder; the quality of the imprint, or the continued registering of the D-roll with the plate or plates.

10 A still further object is to provide a machine wherein the opposite bearings for the shaft carrying the D-roll, may be minutely adjusted simultaneously, radially of the form or plate cylinder.

15 A still further object is to provide a machine with a web re-winding mechanism which will automatically adjust its speed of rotation with each increase of the diameter of the roll thereon, thus permitting the paper 20 web to be run through the machine and to be re-wound after receiving the imprint.

A still further object is to so arrange the re-winding mechanism that a continuous web 25 of tissue or other thin paper or material may be wound with the web in a manner to prevent the smudging of the work.

A still further object is to provide a machine wherein the paper may be fed directly to the machine without having previously 30 been dampened, thus avoiding the shrinkage of the paper, the removal of the sizing of the paper, and the labor and expense incidental to such dampening and such refinishing or recalendering of the paper.

35 A still further object is to provide a machine with a damping mechanism which will operate continuously during the feeding of the paper, to transfer an even, thin film of liquid to the surface of the paper in a manner to cause the paper to readily take up the 40 ink from the intaglio or under cuts of the plate.

A still further object is to provide in such a mechanism a main reservoir and an auxiliary reservoir for the liquid, and a pipe connection between the two whereby the liquid 45 will be supplied to the latter from the former in quantities to maintain a substantially constant level therein, and means whereby 50 said supply will be automatically cut off during intervals when the D-roll is out of gear and the paper is not being fed relative thereto.

A still further object is to provide a machine 55 of this character wherein the plate or plates will be automatically wiped and polished and the paper will be dampened just prior to being fed thereto and while passing through the machine.

60 A still further object is to provide a machine of this character wherein the printed web will be fed from the form or plate cylinder in a manner to avoid any likelihood of the fresh ink being smeared.

65 A still further object is to provide in such

a machine, means whereby the printed web will be subjected to such heat as will rapidly dry the ink and remove the moisture from the paper by heat drying, without injury to the paper itself. And a still further object is to provide a machine wherein the inking, wiping and polishing of the plate or plates, and the feeding of a continuous web of paper and the damping thereof, will be done in such sequence and in such synchronization with relation to each other as to permit the machine to be operated substantially automatically and continuously.

The invention consists in the novel features of construction and combination of parts hereinafter set forth and described and more particularly pointed out in the claims hereto appended.

Referring to the drawings: Figure 1 is a side elevation of a machine embodying my invention with various parts thereof broken away to disclose parts of the mechanism behind same; Fig. 2 is an end view of the machine with the various inking rollers and cylinders partly broken away to more clearly determine the relation thereof to each other; Fig. 3 is a section through the printing and wiping mechanism; Fig. 4 is an end view of the D-roll; Fig. 5 is a detail view of the toothed roll of the blanket mechanism, in perspective; Fig. 6 is a detailed perspective view of the wiping and polishing cloth tensioning roll; Fig. 7 is a detail perspective view of the feeding side of the printing mechanism and its appurtenances; Fig. 8 is a detail perspective view of the controlling lever; Fig. 9 is a detail view of the D-roll starting gear and the plunger pin carried thereby; Fig. 10 is a detail view of the abutment on the end of the D-roll; Fig. 11 is a diagrammatic view of the electrical circuits incidental to the machine, and Fig. 12 is a perspective view of the damping mechanism spaced away from the D-roll.

Like numerals refer to like parts throughout the several views.

In the embodiment of my invention shown in the drawings, I have shown at 21 the frame designed more particularly for the printing mechanism, and at 22 a frame for the wiping and polishing cloth roll and the paper web mechanism, together with the re-winding mechanisms for the cloth and the web.

Mounted in the frame 21 is the main power shaft 23 which may be driven from any desired source of power, a pulley 24 being shown.

Mounted above the main power shaft 23 is the form or plate cylinder 25 which is driven by a shaft 26 having mounted thereon the last of a chain of gears 27 driven from the shaft 23.

Carried by the frame 21 adjacent to the cylinder 25, is an ink fountain and feeding

and spreading roll mechanism 28, the details of which being immaterial to the invention will not be described. Any desired type of inking mechanism may be employed. This mechanism is driven by a gear carried by the shaft 26.

A shaft 29 is mounted in the frame 21 adjacent to the shaft 26 from which it is driven by a chain and sprocket mechanism 30. This last mentioned shaft has keyed or otherwise secured thereon, a bevel gear 31 and one member of a clutch 32, and has loosely mounted thereon a sprocket wheel 33, carrying the other member 34, of the 15 said clutch, thus permitting said sprocket wheel 33 to remain idle or to be caused to rotate with the said shaft. This construction is provided for the purpose of permitting the wiper feed mechanism to be thrown 20 in and out of gear at will.

In presses of this character, it is necessary to ink the plate or plates, to wipe the ink from the upper surface thereof leaving the intaglio design or under surface filled with 25 ink, and thereafter to polish the upper surface so as to avoid streaking or spotting of the imprint taken therefrom. Various means have been provided to perform these operations, in different types of machines, 30 varying from the machine wherein both are done by hand, to those wherein the wiping is mechanically done and the polishing is done by hand, and those wherein each plate is subjected to the action of first one set of 35 cloths for wiping and then a second set of cloths for polishing. In the present machine, however, I have embodied these steps in practically a single operation, ranging from wiping to polishing, with regard to 40 the different positions of the parts during each rotation of the plate or form cylinder. In addition to this, I so construct and arrange the wiper feed mechanism that any likelihood of the plates being streaked is 45 obviated. This mechanism comprises two rollers 35 and 36 mounted in bearings or frames 37-38 respectively on opposite sides of the form or plate cylinder 25, and in close juxtaposition thereto. The frames 37 50 and 38 are seated in ways in the frame 21 and are capable of lateral movement which is imparted thereto simultaneously with the actuation of the wiper feed mechanism. This lateral reciprocation is imparted to 55 the frame 38 by means of a strap 43 within which is an eccentric 44 mounted on a shaft 45 which is driven from the said gear 31 through a bevel gear 46. The shaft seated in the bearings 37 is reciprocated by means 60 of an arm 39 carried thereby and acted upon by an eccentric 40 carried on the shaft 41. The rollers 35 and 36 are idlers. The frame 21 has mounted therein two parallel rollers 47 and 48 of resilient material, preferably soft rubber, disposed one above the

other in bearings which are adjustable toward and from each other to regulate the pressure of these rollers upon each other. Said rollers are driven at equal velocity by intermeshing gears on the shafts thereof, 70 a sprocket wheel 49 carried by one of said shafts, and a chain 50 meshing therewith and with the sprocket wheel 33. On the other end of the frame 21, are the wiper cloth guide rollers 51 and 52. To effect- 75 80 85 90 95 100 105 110 115 120 125 130
ively wipe and polish the plates, it is necessary to place the cloth under such tension as to always hold it perfectly taut, thus causing it to press hard upon the plates. As the said cloth, which in the drawings is indicated at 53, is drawn from a point beyond the plate or form cylinder, such tensioning must be accomplished by a resistance applied thereto on the forward side of said cylinder, each side being determined with relation to the direction of feed of the cloth. This tensioning means preferably comprises a metallic roller 54 having a plurality of knurled circumferential ridges thereon, as 55, adapted and designed to afford the requisite gripping area, and carrying a brake drum 56. The said roller bears upon the roller 35 and is driven by its frictional engagement therewith. It is secured to its shaft by means of a feather, thus being permitted to have lateral movement with the roller 35. The bearings for the rollers 35 and 54 are themselves incapable of lateral movement, but are adjustable relative to each other by means of the adjustment screw 35^a, to regulate the pressure of the roller 54 on the roller 35, governing the slippage of the cloth and its backing, in feeding between said rollers; and both said bearings are adjustable toward and from the form or plate cylinder by means of the racks 54^a carried by the bearings of the roller 54, and the pinions 54^b in mesh with each said rack, in order to permit the regulation of the quantity of surface of the wiper cloth contacting with the plate or plates on said cylinder. The pinions 54^b are carried on a shaft 54^c having a worm wheel 54^d actuated by a worm 54^e, thus adjusting the said rollers 54-35 by a simultaneous equal movement of both ends thereof. The rotation of the roller 54 is retarded by means of a brake mechanism consisting of a brake head 57 carried by a screw mounted in suitable supports on the frame 21, and carries a brake shoe 58 preferably of fiber, and means setting said brake and regulating the pressure therefrom comprising a jam nut 59 and a set nut 60 on said screw, by means of which construction, the strain on the wiper cloth may be regulated to a nicety.

Mounted on a spring pressed oscillating frame 61 between the rollers 51 and 52 is a take up roller 62.

To relieve the cloth 53 as much as possible from the strains thereon, I provide a strong backing therefor comprising an endless belt 63 running about the rollers 35, 36, 47, 48, 51, 62, 52 and 54, which belt is made of strong reinforced material, and takes up enough of the strain to permit the use of a wiping cloth of the desired texture. To facilitate the threading of the wiping cloth 10 through the machine, I provide said belt with a flap 64 under which the end of the continuous strip of cloth may be inserted.

In the lower part of the frame 21, is a guide roller 65 for the wiper cloth, to facilitate the feeding and rewinding thereof. The frame 22, carries similar rollers 66, 67 and 68, and also a removable roller 69 for the roll of cloth. If desired polished rods 20 above referred to.

The wiper being in the form of a continuous web and having a substantially continuous feeding movement, it is desirable to provide means whereby it will be re-wound, to 25 conveniently store same after use, and also to permit it to be run through the machine a second time with the reverse side operative. It is also necessary to provide a rewinding mechanism, the velocity of which 30 will be automatically controlled to conform to the variance in the diameter of the roll of cloth on the spindle at any time. This last mentioned mechanism preferably comprises a shaft 70 mounted in the frame 22 carrying one member of a friction clutch 71 thereon, and having loosely mounted thereon a sprocket wheel 72 carrying the other member of said clutch. The said sprocket wheel 35 is driven from the shaft 23 by means of a sprocket wheel 73 thereon, and a chain 74. The wiper strip when wound on the spindle or shaft 70 with the dirty side outward, may be fed therefrom without changing the position of the parts, it being merely necessary 40 to release the clutch 71 so as to allow the shaft 70 to run as an idler, said clutch being set through the nut 75 to permit such adjustment of the machine and the regulation of the friction clutch itself. After running 45 the cloth through the machine the second time, I wind it upon a shaft 76 mounted on the frame 21 and driven through the member 77 of a friction clutch carried thereby, a sprocket wheel 78 carrying the 50 other member of said clutch a sprocket chain 79 and a sprocket wheel 80 carried by the main driving or power shaft 23. I arrange the shafts 70 and 76 in the positions shown 55 for convenience in running the machine, but such may be differently positioned if desired.

Mounted on a shaft 81 above the form cylinder and parallel therewith, is the D-roll 82 carrying a suitably backed blanket 66-83. The said roll is driven mainly through

frictional engagement thereof with the plate or plates on said cylinder; and to regulate the pressure necessary to develop the required pressure, I mount the said shaft 81 in bearings 84 housed in openings in the frame 21 each supported by a plurality of springs 85. Acting on said bearings respectively, are set screws 86 mounted in said frame, each of which carries a worm wheel 87 actuated through a worm 88, the shank of which carries a handle as 89 whereby the said bearings may be simultaneously raised or lowered to regulate such pressure. In under-surface printing, such pressure, to secure a high class of work, must be minutely 80 regulated, and by the worm, worm wheel and screw construction described, the quantity of movement of the bearings may be regulated to the thousandth of an inch, constituting a micrometer adjustment. The 85 simultaneous adjustment of both bearings is desirable in that after the machine is once set up, the subsequent adjustment to compensate for a variance in the thickness of the blanket through stretching, or of the 90 backing through substitution or wear, may be accomplished without destroying the parallelism of the plate or form cylinder and the D-roll, thus insuring accuracy and speed of adjustment. The blanket is secured 95 to the D-roll by having one end thereof clamped to the forward edge of a recess in said roll, by means of a clamp 90 and the other edge by means of a roller 91 having a plurality of alined teeth 92 and a ratchet 100 wheel 93 engaged by a pawl 94 mounted on the end plate of said roll. The blanket is stretched about the D-roll and the backing between it and said roll, until it is perfectly smooth, by turning the roller 91, the pawl 105 and ratchet holding all that is taken up. It is essential that the blanket be kept taut and as ordinarily in use the blanket is liable to stretch and wrinkle, in a manner to spoil the work unless the machine is stopped and 110 the slack taken up, I provide an automatically operated mechanism which will take up any slack with each rotation of the D-roll, thus preventing the development of material slack and avoiding the necessity 115 for frequent stoppage of the machine, and hence increasing its capacity to that extent, and permitting the use of a continuous paper web without loss through imperfect imprints or the breaking of the web. This 120 mechanism comprises a lever 95 pivoted to the head of the D-roll and normally projected outwardly until checked by the stop pin 96, by a spring 97. The outer face of this lever has an outwardly presented abutment 98 projected beyond the periphery of said roll head. Mounted adjacent to the D-roll and projecting into the path of the lever 95 is a disk 99 having a resilient rim 125 100 adapted to engage the abutment 98. 180

This rim is fairly stiff, being capable of depression only when the blanket is sufficiently tense. The degree of resilience of the disk determines the tension of the blanket, and should be such as to not subject said blanket to breaking strains. The lever 95 has pivoted to its free end a spring pressed pawl 101 adapted to engage the teeth of the ratchet wheel 93 at a point to rotate same each time 10 the lever is depressed.

The D-roll is normally driven through its frictional engagement with the plate or form cylinder. In a machine of this character wherein high grade work is done, it is essential, to secure speed, that the D-roll and form cylinder should always register so as to bring the recess in the former to the proper position relative to the plates or forms. To drive the D-roll and form cylinder by intermeshing gears carried thereby, has been found unsatisfactory in practice as not securing the necessary degree of accuracy, and consequently a frictional drive of the former is reasonably requisite. Owing to slight variance in the diameters of the D-roll through a stretching of the blanket, and a tendency of the said roll to over run slightly as it ceases to engage the form or plate at its recessed point, I provide starting means whereby the said roll will receive a positive starting impulse at the proper interval relative to the rotation of the plate or form cylinder, and other means synchronized therewith, whereby the said roll will be locked against movement subsequent to or simultaneously with said disengagement, thus insuring an accurate registering of the D-roll with the plate or plates at the initiation of each rotation, and preventing such an over run of the said roll as would interfere with securing such. I also provide means whereby both such means may be thrown out of gear, and a permanent lock set so as to maintain said D-roll stationary when it is desired to stop the printing temporarily for any purpose, as running in fresh paper, or changing the wiper cloth. In the drawings, I have shown this mechanism in a form which I have found preferable to accomplish such results, and shall now describe same.

Loosely mounted on the shaft 81 is a gear 102 having a transverse opening therethrough in which is mounted a plunger pin 103, held retracted by a forked spring 104 straddling said pin and engaging suitable slots therein. This gear is adapted to mesh with and be continuously rotated by the gear 105 mounted on the form cylinder 25. The side of the pin 103 is beveled on the face thereof presented in the direction of rotation of the gear 102, and said gear is spaced away from the frame 21 sufficiently to afford a clear field of rotation for said pin. Carried by the side of the D-roll adjacent to

said gear 102, and substantially diametrically opposite the recess in said roll, is a fixed abutment 106 projected beyond said roll toward said gear with an inclined face presented oppositely to the direction of rotation of the gear, so as to be in the path of the pin 103 when said pin is projected into its operative position. Pivotally mounted on the frame of the machine so as to be capable of being interposed therebetween and the gear 102, is a lever handle 107 having a beveled abutment 108 thereon rising from the lever 107 and descending thereto substantially at right angles. The said lever handle carries a latch member 109, preferably a spring tongue, adapted to sustain it in the raised position. One end of the said lever carries a tappet 110 adapted to operate a circuit closer when the lever is raised, to close an electrical circuit, and to open it or permit it to automatically open when the lever is lowered. This circuit closer comprises a fixed terminal 111 and a spring contact 112 opposed thereto, and adapted to be engaged by the tappet 110. The D-roll 82 carries on its other end a band 113 preferably of metal, and mounted adjacent to said band is a brake shoe 114 carried by a swinging brake head 115 having a projecting lever arm 116. Mounted on the same shaft as the said brake head, is a lever arm 117 carrying an adjustment screw 118, adapted to engage the brake lever arm 116, and set the brake, and an armature 119 on the free end thereof.

Carried by suitable supports 120 mounted on and insulated from the frame 21, is an ordinary electro magnet 121. One terminal of the magnet is in electrical connection with a source of electrical supply, as one pole of an ordinary dynamo circuit, and the other is in similar connection with a commutator brush 122 in permanent contact with a shaft 26. Pivotally mounted adjacent to the said commutator, and in electrical connection with the other pole of said circuit, is a spring pressed brush 124 normally held away from said commutator by a stud 125, and adapted to contact with a projection 126 carried by said commutator, with each rotation thereof, and to be raised thereby slightly to insure a good contact and the return to normal. This arrangement results in a good electrical contact and that timely energizing and deenergizing of the magnet, necessary to secure a timely braking action on the D-roll, and a release thereof which will cause the braking action to be but long enough to prevent any tendency of the D-roll to over run.

The electrical connections of the machine aside from those feeding the resistance coils in the several cylinders and rollers and the drying attachment, to be hereinafter referred to, are illustrated in Fig. 11 in a

conventional way. In said view, the terminal wires of the dynamo or other source of power are shown at 127 and 128, the said wire 127 having one lead to the magnet 121, 5 and the other said wire, 128, having one lead 130 through a lamp 131 to the brush 124. The other terminal wire 132 of the magnet leads to the brush 122 and has a branch wire 133 leading therefrom to the 10 switch member 112. The switch member 111 is in direct electrical connection by the wire 134 with the terminal wire 128. By this wiring, it will be observed that when the lever 107 is lowered to initiate the rotation of the D-roll, the circuit closer 111, 112 is open and the magnet 121 is energized 15 solely through the circuit including therein the commutator 123 and the commutator brush 124, thus setting the brake 114 momentarily once during each rotation of the 20 D-roll and the form cylinder; but that when it is raised, the said circuit closers are closed, thus energizing the magnet by a continuous circuit, setting said brake during all periods 25 when the means starting the D-roll is thrown out of the operative position. This arrangement insures such a timely stoppage of the D-roll after it has passed the point of frictional engagement with the plate on the 30 plate cylinder, as to prevent any over run thereof under momentum, and such a holding thereof when not printing, as will avoid any creeping from any source whatever. It will be observed that the pressure exerted 35 by the brake 114 may be so regulated by the set screw 118 as to permit the rotation of the D-roll through its frictional engagement with the plate cylinder, in case the lever 107 is raised before the completion of 40 the rotation, while instantly checking all movement when the flat of the said roll is tangent to the form cylinder.

The paper feed mechanism comprises three coöperating mechanisms, that relating 45 to the support of the paper roll and its feed to the D-roll and form cylinder; a damping attachment by means of which the web may be fed preferably dry before, and be wetted down only as it passes through the machine, 50 and the drying and re-winding mechanism by means of which the web after receiving the imprint is put in convenient form for subsequent treatment, or removal from the press, without danger of being blurred or 55 smutted, and without limiting the speed of operation of the machine. The first two of these are reasonably necessary in a machine of this character, but the last may be modified or dispensed with if desired.

60 Supported on the frame 22 is a paper reel 135 adapted to receive a roll of paper web 136. Also supported by said frame is the wetting mechanism between which and the reel 135 are guide rods or rollers 137-138.

65 Mounted on the frame 21 adjacent to the

D-roll, are the guide rollers 139-140, over which the web passes, and by which it is trued up before passing to the printing mechanism. The rollers 139-140 are adjustable toward and from each other by 70 any desired means as the set screw 141.

The damping mechanism comprises a fountain 142 in which are mounted two spreading rollers 143-144 adapted to be submerged in the water or the water and chemicals or solvents, in said fountain. The roller 144 may be adjusted toward and from the roller 143 by means of the set screw 145, thus regulating the quantity of fluid carried over by the roller 143 to the distributing roller hereinafter referred to. Mounted above one of these rollers as 143, and adapted to receive a thin film of moisture therefrom, is a distributing roller 146 over which the paper web 136 passes to receive 85 sufficient moisture on its lower surface to soften the paper and prepare it for receiving an imprint. These rollers 143, 144 and 146 are driven solely through the paper web passing over the last named. I have found 90 in practice that by damping one side of the paper only and immediately before feeding it to the printing mechanism, the surface to be printed may be softened sufficiently to give that flexibility and affinity 95 for ink necessary to insure the proper taking up of the ink deposited in the intaglio cuts, and that slight depression into said cuts incidental thereto, without so destroying or injuriously affecting the sizing of the 100 paper, as to necessitate a refinishing thereof after drying. I space the damping mechanism away from the printing mechanism as shown in order to afford ample opportunity for the moisture to become 105 thoroughly diffused over and to permeate the surface of, the paper before entering the printing mechanism, although I have not found this absolutely essential. It is preferable, however, when running at high 110 speed. To meet all the requirements of use however, I provide the machine with a supplemental damping mechanism consisting of the fountain 147 in which the roller 140 runs so as to be capable of applying water 115 to the paper just as it enters the printing mechanism. The fountains 142 and the supplemental fountain 147 each with its spreading roller, may be used in conjunction with each other, or either may be used 120 alone.

To replenish the supply of water in the fountain 142, I place said fountain in communication with a reservoir 148, through a pipe 149. The inlet to said pipe is controlled by a ball valve 150 the ball of which is of magnetic material, actuated through a magnet 151, the terminals of which are in circuit with a source of electrical supply through a relay 152 actuated 130

through the operation of the lever 107, the wiring being such that when the lever is raised, the relay will open the local circuit and close the valve, thus shutting off the supply of water flowing from the reservoir 148 when the feed of paper ceases, and that when the said lever is down and the press is running, water will be fed to said fountain in quantities substantially equaling that being constantly used.

I find that under some circumstances it is desirable to provide the roller 143 with interior heating appliances, as resistance coils not shown.

The wiring of the circuit controlling the relay 152 and the local circuit itself, is substantially as follows: The terminals 175—176 of the magnet of the relay are respectively in electrical communication with one switch member 112, and with one pole of the main circuit. The terminals 177 and 178 of the magnet 151, are respectively connected to one pole of the local circuit, and with the contact of the said relay, the lever of said relay being connected by the wire 179 with the other pole of said local circuit, an arrangement which reverses the ordinary telegraphic relay, thus causing the closing of the local circuit when the relay magnet is energized. This construction of relay being well known in the arts, the parts thereof are referred to without special reference letters and are not described in detail.

Disposed above the D-roll 82 so as to allow a clear field for the printed web, is a heated roller 180, and extending from this roller to the frame 22 are a plurality of resistance coils 181 suitably incased and inclosed in a covered drying box 182. The said frame 22 has a suitable guide rod or roller 154 and a winding reel 155 below it for receiving and re-winding the printed web. This reel is driven by a gear 156 carried thereby and a gear 157 driven by a friction clutch 158, one member of which carries a sprocket wheel 159 driven from a sprocket wheel on the shaft 70 by a chain 160. This friction drive is provided to compensate for the variance in the speed of the reel 155 due to the increasing diameter of the roll of web. The shaft of said gear 157 is composed of two concentric shafts, one of which carries the said gear and one member of the clutch, and the other of which carries the sprocket 159 and the other member of said clutch. The frame 22 also carries a reel 161 for a roll of thin paper adapted to pass about a guide roller or rod 162, and to be wound within the roll of printed web, to prevent the various plies adhering to each other.

The plates 172 on the form cylinder 25 are heated by means of resistance coils indicated conventionally at 173 within said cylinder, the terminal wires for said coils and the contacts by means of which the circuit is caused

to pass continuously through said coils, being shown at 174. The plates 172 are ordinary engraved plates properly bent to shape, and may be attached to the cylinder 25 in any desired manner. The abutting ends of said plate or plates are preferably so positioned as to approximately register with the flat of the D-roll, thus allowing for the slight excess movement of the form cylinder upon each rotation thereof.

The operation of the herein described printing machine is substantially as follows: When power is applied to the main shaft 23 through the pulley 24, the form cylinder 25 is continuously rotated through the gear system 27, and the inking mechanism is driven from the gear 105, thus inking the plate or plates immediately after an impression has been taken therefrom.

While the various mechanisms embodied in the machine are or may be all driven from the shaft 23 in such synchronism as to have each perform its functions in a timely manner relative to the others, the operation of each such will be described independently of the others in the interests of perspicuity. The distributing and form rollers 28 ink the plate or plates in the usual and well known manner which is not material to the invention and will not be described in detail.

While the form cylinder 25 rotates continuously, the wiper cloth feed mechanism may be thrown in and out of gear through the clutch 32 to cause the cloth to be fed through the machine or not as desired. The bearings or frames 38 and the shaft mounted in the bearings 37, however, and their rollers 36 and 35, are given continuous lateral reciprocation through the strap 43 and eccentric 44 and the arm 39 and eccentric 40, said eccentricities being respectively from the bevel gear 31 through the shafts 45 and 41 in a manner to cause both said rollers to have a simultaneous equal movement in the same direction. To start the feeding movement of the wiping cloth, the members of the clutch 32 are thrown into mesh with each other, thus causing the endless belt 63 to be carried around the various rollers 35, 36, 47, 51, 62 and 52 by the rollers 47 and 48, which last mentioned rollers are positively driven by the chain and sprocket mechanism 50. The end of the wiper cloth 53 is then passed under the rollers 66, 68 and 65 and inserted under the flap 64 of the belt 63, whereafter it is fed relative to the form cylinder by being passed with said belt as a backing under the roller 54, over the roller 35 and under the form cylinder 25 to the roller 36 on the opposite side thereof beneath the inking mechanism, to the rollers 47 and 48 by means of which, as heretofore stated, it receives its feeding movement. The speed of rotation of the roller 54 may be retarded by setting the

brake 58 on the drum 56 by the braking mechanism described, the construction of said roller and its engagement with the roller 35 preventing such slippage of the cloth and the endless belt as will prevent said cloth being drawn perfectly tight across the plates 172 on the cylinder 25. The adjustment screws 35^a may be used to regulate the pressure of the roller 54 against the roller 35 which will aid in securing the desired tension of the cloth, and the rollers 35 and 54 may be moved toward and from the form or plate cylinder by the actuation of the worm 54^c, to secure a sufficient wiping surface of the cloth to thoroughly wipe, clean and polish the plate or plates. As the cloth leaves the rollers 47 and 48 it is passed around the shaft 56 which at this stage is run as an idler, and the guide rollers or rods 65 and 67 to the shaft 70 which is driven by the friction clutch 71 at a speed varying with the diameter of the roll of cloth thereon, the inked side of the wiper cloth being presented outwardly. The said cloth in passing under the form cylinder, has a general direction of movement opposite to that of the contacting surfaces of the plates and by reason of the lateral reciprocation of the rollers 35 and 36, a substantially circular movement is imparted thereto which tends to not only thoroughly wipe the surface of the said plate or plates, but to scrub and polish same in a manner to avoid any possibility of streaking through the texture of the cloth itself. It will be observed that the same cloth wipes and polishes the plate or plates, and that these functions are performed at different points of the cloth so that a fresh clean portion thereof is always presented as a finishing portion. Hence portions slightly soiled in wiping a portion of the plate or plates upon one part of a rotation is used for removing the greater portion of the ink from the plate or plates during a succeeding part of such rotation and subsequent rotations; and is disposed ultimately adjacent to the inking rolls so that the subsequent wiping and polishing is done by portions of the cloth which are gradually cleaner proportionately to the distance from said rolls. This construction is important as it results in a machine wherein the wiping and polishing is done by a cloth which is never thoroughly saturated with ink and wherein the substitution of fresh clean cloth does not require the shutting down of the machine. It is also desirable in that the cloth being pressed against the plate or plates by the tensioning of the cloth and a reinforced flexible backing therefor, a perfect engagement of the wiper with said plate or plates is assured. This tensioning of the cloth is also an important feature, as it insures the thorough cleansing and polishing

of the plate or plates. When the entire strip of cloth has been run through the machine and wound upon the shaft 70, the clutch 71 is released through the nut 75 and the end of the roll of cloth on the shaft 70 is passed under the rollers or rods 68 and 65 and fed through the machine as above described only with the reverse side contacting with the plate or plates. After this second run, to avoid obstructing the machine, the clutch 77—78 on the shaft 76 is set and the cloth is wound thereon. While the machine is not printing, the lever 107 may be raised, thus permitting the gear 102 to run idly as will more fully appear hereinafter. When said lever is thus raised, the tappet 110 actuates the circuit closer 111—112 to close the circuit energizing the magnet 121, thus setting the brake shoe 114 and preventing any excess movement of the D-roll. The closing of this circuit also actuates the relay 152, thus closing the valve 150, and cutting off the supply of water being fed to the fountain 142. Said lever is held in the raised position by the latch 109 which springs outward and engages the top of the frame 21.

In printing, the end of the paper web 136 is passed around the guide rods 137 and 138, over the roller 146, between the rollers 139 and 140, between the D-roll 82 and the plate or plates 172 on the form cylinder 25, upward and over the drying roller 180, through the drying box 182 over the coils 181 therein, and about the guide roller or rod 154 to the reel 155. When the web is so threaded, the machine is ready for the start. The power being on, the form cylinder 25 is rotated, but the flat of the D-roll being tangent thereto, or on a plane parallel to a line tangent thereto, it is necessary to give said D-roll an initial positive impulse sufficient to bring it into frictional engagement with the plate or plates 172 on the form cylinder. To start the printing operation, it is merely necessary to drop the lever 107 between the gear 102 and the side frame 21, the contacts 111 and 112 thus being permitted to spring apart, deenergizing the magnet 121 and releasing the brake 114. As said gear rotates, the pin 103 carried thereby engages the bevel 108 on said lever and is forced inwardly to a point when the bevel on said pin engages the bevel on the abutment 106 on the side of the D-roll. Thereafter said D-roll is turned by said gear to an extent equaling the length of the bevel 108 which is sufficient to bring the D-roll into the requisite frictional engagement with the plate 172. With the breaking of the circuit through the switch members 111—112, the brake shoe 114 is released through gravity and raises the armature 119 from the core of the magnet 121. Substantially simultaneously with the engagement of the D-roll with the plate 172, 125

the pin 103 passes from the abutment 108 and recedes into its socket, permitting the subsequent rotation of the D-roll to be under friction solely. It will thus be observed that 5 the D-roll receives one positive impulse with each rotation thereof, and thereafter is rotated at the same peripheral velocity as the form cylinder and plate or plates thereon. The relative diameters of the form cylinder 10 and of the D-roll, the respective gears 102 and 105 being of equal diameter, is such that said D-roll gains slightly on said pin 103, thus providing a slight interval of rest between successive rotations. If it be found 15 that the pressure of the D-roll on the plate or plates of the form cylinder, is too great or insufficient to secure a good imprint, or to insure the proper rotation of the former, this pressure may be regulated by turning 20 the handle 89 in the proper direction, thus either permitting the springs 85 to raise the D-roll bearings, or compressing said springs and thus lowering said bearings. The worm and worm wheel construction described not 25 only permits a micrometer adjustment of this pressure, but simultaneously adjusts both bearings in the same degree, thus obviating the difficulties encountered when each bearing must be adjusted separately. 30 As the D-roll approaches the limit of its rotation, the tappet 126 approaches the brush 124, and simultaneously with the disengagement of the plate on the form cylinder and the D-roll through the flat thereof assuming 35 a position substantially tangent to said plate, said tappet engages said brush momentarily closing the circuit to the magnet 121 and setting the brake 114 through the attraction of the armature 119 the oscillation of the lever 117 and the power applied through the 40 screw 118 to the lever 116 carrying the brake head 115. This instantly checks the D-roll and overcomes any tendency thereof to over run under momentum. As said tappet leaves 45 said brush, however, the circuit is again broken, deenergizing said magnet, releasing the brake and freeing said D-roll preparatory to the next rotation. The duration of 50 said contact should be such as to hold said D-roll stationary for a period substantially equaling the rest of the D-roll, although as the starting impulse is positive, the brake 114 will not materially interfere with the proper and timely initiation of the start of 55 the rotation of said D-roll. The D-roll thus comes to rest after each rotation, the duration of which rest is dependent solely upon the gain of said roll upon the gear 102 during a single rotation. Whether this be relatively more or less (it never being large) 60 the D-roll always starts at the same point relative to the plate, this interval of rest compensating only for those differences in the diameters of the form cylinders and 65 plate or plates thereon, and of the D-roll

which are unavoidable mechanically and by reason of the varying thickness of the blanket and its backing. Thus it will be observed that the D-roll, in printing, is moved intermittently only, being brought to a dead 70 stop and positively started, yet moving during the interval when the imprint is being taken, in perfect unison with the plate and plate or form cylinder; and that notwithstanding the slight differences in the diameters of the form cylinder and the D-roll, said roll is always in perfect register with the plate or plates upon the initiation of the rotation of the former. 75

Inasmuch as the D-roll is turned during 80 the printing interval through frictional engagement with the plate or plates on the form cylinder, and as the quality of the work depends upon an even and continuous rotation of the D-roll and a perfectly 85 smooth blanket, the capacity of the machine as well as its efficiency is materially increased by the automatic blanket take up described. Upon each rotation of the D-roll, the flexible rim 100 of the disk 99 engages 90 the abutment 98 of the lever 95, and if the blanket is properly tensioned, the resistance to the depression of said lever by the blanket, will be greater than that exerted by the rim 100, thus causing the depression 95 of the latter and permitting the lever abutment to pass same without impeding the movement of the D-roll. If, however, there be any slack in the blanket, the lever 95 will be depressed, the pawl 101 carried 100 thereby turning the shaft 91 through the ratchet wheel 93 thereon, thus taking up such slack, the pawl 94 holding all slack taken up. The rotatable disk 99 is preferable as the circular rim thereof not only 105 presents a contact surface which varies without materially changing the relation of the various parts, thus avoiding wear, at one point, but because the said disk being free to turn, has such movement as to secure 110 a rolling engagement and disengagement with said lever upon each rotation. 115

The rollers 143 and 144 in the damping mechanism take up water as they are turned and apply it to the roller 146 which in turn applies it to the under side of the web, being that side which contacts with the plate or plates. These rollers being spaced several feet from the form or plate cylinder, are used only when the press is running at high 120 speed, a short interval being desirable to permit the water to permeate the surface of the paper. When desired, however, the roller 140 may be used alone to dampen the paper immediately before entering the 125 printing mechanism. This latter I have found to be quite as efficient as the other damping mechanism, particularly when the speed of the press is somewhat lower. With either damping mechanism, however, the re- 130

sult attained is the superficial damping of the paper immediately prior to its entering the printing mechanism, thus obviating the present practice of wetting down by 5 dampened cloths for a considerable period prior to use, a practice which frequently results in the partial or entire removal of the sizing of the paper and the necessity for refinishing the paper after printing thereon.

10 The paper is fed through the machine by the D-roll and plate or form cylinder, and hence the feeding thereof will be discontinued with the raising of the lever 107. As the paper leaves the D-roll, it passes 15 about the drying roll 180 and through the heating box 182 over the electric heater 181 where the dampness is thoroughly removed from the paper and the ink of the impress itself dried more or less perfectly. From 20 the heating box 182 the web passes over the guide rod or roller 154 to the rewinding reel 155 where it is rewound preparatory to further operation or treatment. To avoid a possible adhesive of the printed web, a tissue web from the reel 161 is laid and wound 25 between the successive plies of the re-wound web as shown.

The hereinbefore described operations are carried on substantially simultaneously as 30 to time but in sequence as to the general result, and with practical continuity, the machine being capable of running at high speed, the nature and quality of the work being considered. It has been found in 35 practice that the web may be run through the machine and be dampened, printed and dried as described without likelihood of breakage thereof, and with practically uniform quality of work. The dampening of 40 the paper immediately prior to taking the impression has been found to impart to the high grade paper required in this class of work, all the characteristics essential to secure a good imprint while not causing the 45 ink to spread, or injuring or destroying the finish of the paper.

In the foregoing description of the operation of the machine, I have referred more particularly to the various operations in 50 printing a continuous web without referring in detail to the operation of all the mechanisms incidental thereto, the power transmissions and the other minor mechanisms, the operation of such being apparent 55 from the detailed description of their construction and arrangement.

The raising or lowering of the lever 107 has the function of not only controlling the movement of the D-roll but also the electrical circuits permanently energizing the 60 magnet 121 and actuating the relay 152, or deenergizing it, as it may be required to supply water or other solvent to the fountain 142. The intermittent circuit is not 65 controlled by said lever handle however.

The operation of the means cutting off the supply of water is substantially as follows: The magnet 151 is included in a normally closed local circuit, and the terminal wires of the relay magnet are included in the main 70 circuit through the switch 111—112. Hence when the lever 107 is lowered, said switch being open, the local circuit is closed, thus energizing the magnet 148 and opening the valve 150 by raising the ball thereof. When, 75 however, the lever is raised and said switch is closed, the circuit to the magnet 121 is not only closed, but the circuit including the relay magnet is simultaneously closed thus breaking the local circuit and permitting the 80 ball of the valve to drop and close said valve.

It is not my intention to limit the invention to the details of construction shown in the accompanying drawings, such being 85 merely that form of the invention which has been found satisfactory in one class of under surface printing. In order to increase the capacity of a machine, the dimensions of the various parts may be increased to accommodate the machine to a greater number of plates, or a wider web, or the various mechanisms may be multiplied so as to adapt the machine to the use of several webs, a construction which has not been illustrated 95 or described as involving no modification of the invention, but merely a duplicate of parts.

Having described the invention, what I claim as new and desire to have protected 100 by Letters Patent is:—

1. In a printing machine, the combination with a form or plate cylinder, a platen cylinder, means rotating said cylinders and an inking mechanism, of a wiping and polishing mechanism comprising a continuous strip of absorbent material means whereby said strip of absorbent material is continuously fed relative to said form or plate cylinder when said cylinder is rotated, whereby 105 the soiled part of the strip acts as a wiper and the fresh part thereof as a polisher, and means tensioning said material, whereby an extended portion of said strip is pressed 110 against the form or plate on said cylinder. 115

2. In a printing machine, the combination with a form or plate cylinder, a platen cylinder, means rotating said cylinders and an inking mechanism, of a wiping and polishing mechanism comprising a continuous strip 120 of absorbent material means whereby said strip of absorbent material is continuously fed relative to said form or plate cylinder when said cylinder is rotated, whereby the soiled part of the strip acts as a wiper and the fresh part thereof as a polisher, laterally reciprocating means whereby said material is given simultaneous lateral movement and means tensioning said material, whereby an extended portion of said strip is 125 180

pressed against the form or plate on said cylinder.

3. In a printing machine, the combination with a form or plate cylinder, a platen cylinder, means rotating said cylinders and an inking mechanism, of a wiping and polishing mechanism comprising a continuous strip of absorbent material means whereby said strip of absorbent material is continuously fed relative to said form or plate cylinder from one side thereof toward the inking mechanism when said cylinder is rotated whereby the soiled part of the strip acts as a wiper and the fresh part as a polisher, and means tensioning said material, whereby an extended portion of said strip is pressed against the form or plate on said cylinder.

4. In a printing machine, the combination with a form or plate cylinder, a platen cylinder, means rotating said cylinders and an inking mechanism, of a wiping and polishing mechanism comprising a continuous strip of absorbent material means whereby said strip of absorbent material is continuously fed relative to said form or plate cylinder from one side thereof toward the inking mechanism when said cylinder is rotated whereby the soiled part of the strip acts as a wiper and the fresh part as a polisher, laterally reciprocating means whereby said material is given simultaneous lateral movement, and means tensioning said material, whereby an extended portion of said strip is pressed against the form or plate on said cylinder.

5. In a printing machine, the combination with a form or plate cylinder, a platen cylinder, means rotating said cylinders and an inking mechanism, of a wiping and polishing mechanism comprising a continuous strip of absorbent material means whereby said strip of absorbent material is continuously fed relative to said form or plate cylinder when said cylinder is rotated, whereby the soiled part of the strip acts as a wiper and the fresh part thereof as a polisher, means whereby said feeding means may be rendered inoperative and means tensioning said material, whereby an extended portion of said strip is pressed against the form or plate on said cylinder.

6. In a printing machine, the combination with a form or plate cylinder, a platen cylinder, means rotating said cylinders and an inking mechanism, of a wiping and polishing mechanism comprising a continuous strip, means whereby said strip is continuously fed relative to said form or plate cylinder when said cylinder is rotated whereby the soiled part of the strip acts as a wiper and the fresh part thereof as a polisher, means tensioning said cloth whereby an extended portion of said strip is pressed against the form or plate on said cylinder, and means

whereby said cloth is re-wound after leaving said feeding means.

7. In a printing machine, the combination with a form or plate cylinder, a platen cylinder, means rotating said cylinders and an inking mechanism, of a wiping and polishing mechanism comprising a strip of flexible absorbent material means whereby said strip is continuously fed relative to said form or plate cylinder, whereby the soiled part of the strip acts as a wiper and the fresh part thereof as a polisher, a flexible endless band carried by said means affording a backing for said material, and means tensioning said band and said material, whereby an extended portion of said strip is pressed against the form or plate on said cylinder.

8. In a printing machine, the combination with a form or plate cylinder, a platen cylinder, means rotating said cylinders and an inking mechanism, of a wiping and polishing mechanism comprising a strip of flexible absorbent material means whereby said strip is continuously fed relative to said form or plate cylinder, whereby the soiled part of the strip acts as a wiper and the fresh part thereof as a polisher, a flexible endless band carried by said means affording a backing for said material, a flap on said band, and means tensioning said band and said material, whereby an extended portion of said strip is pressed against the form or plate on said cylinder.

9. In a printing machine, the combination with a form or plate cylinder, a platen cylinder, means rotating said cylinders and an inking mechanism, of a wiping and polishing mechanism comprising a continuous strip of absorbent material a plurality of feeding rollers on one side of said cylinders, a guide roller on the opposite side of said cylinders, a pressure roller bearing on said guide roller and means retarding the rotation of said pressure roller.

10. In a printing machine, the combination with a form or plate cylinder, a platen cylinder, means rotating said cylinders and an inking mechanism, of a wiping and polishing mechanism comprising a continuous strip of absorbent material a plurality of feeding rollers on one side of said cylinders, a guide roller on the other side of said cylinders, a pressure roller bearing on said guide roller, a friction disk carried by the shaft of said pressure roller, and braking means whereby the rotation of said roller may be retarded and controlled.

11. In a printing machine, the combination with a form or plate cylinder, a platen cylinder, means rotating said cylinders, and an inking mechanism, of a wiping and polishing mechanism comprising a continuous strip of absorbent material a plurality of

feeding rollers on one side of said cylinders, a guide roller between said feeding rollers and said cylinders and in close juxtaposition to said form or plate cylinder, a guide roller 5 on the opposite side of and adjacent to, said form or plate cylinder, means whereby said guide rollers are given simultaneous lateral reciprocation, a pressure roller bearing on said guide roller adjacent to said form or 10 plate cylinder and adapted to reciprocate therewith, and means retarding the rotation of said pressure roller.

12. In a printing machine, the combination with a form or plate cylinder, a platen cylinder, means rotating said cylinders and an inking mechanism, of a wiping and polishing mechanism comprising a continuous strip of absorbent material a plurality of feeding rollers on one side of said cylinders, 15 a guide roller between said feeding rollers and said cylinders and in close juxtaposition to said form or plate cylinder, a guide roller on the opposite side of and adjacent to, said form or plate cylinder, means whereby 20 said guide rollers are given simultaneous lateral reciprocation, a pressure roller bearing on said guide roller adjacent to said form or plate cylinder and adapted to reciprocate therewith, means retarding the 25 rotation of said pressure roller, further guides arranged between said feeding rollers and said pressure roller and an endless band passing around or over said guide rollers respectively and between said feeding rollers. 30

35 13. In a printing machine, the combination with a form or plate cylinder, a platen cylinder, means rotating said cylinders and an inking mechanism, of a wiping and polishing mechanism comprising a continuous 40 strip of absorbent material a plurality of feeding rollers on one side of said cylinders, a guide roller between said feeding rollers and said cylinders and in close juxtaposition to said form or plate cylinder, a guide 45 roller on the opposite side of said form or plate cylinder and adjacent thereto, means whereby said guide rollers are given simultaneous lateral reciprocation, a pressure roller bearing on said guide roller adjacent to 50 said form or plate cylinder and adapted to reciprocate therewith, means retarding the rotation of said pressure roller, further guides arranged between said feeding rollers and said pressure roller, an endless band 55 passing around or over said guide rollers respectively and between said feeding rollers, a reel whereby a roll of wiping cloth is supported adjacent thereto, guides arranged between said reel and said pressure roller, 60 a re-winding reel, means whereby said last mentioned reel is frictionally driven, means whereby said reel is released from said driving means, and guides arranged between said re-winding reel and said feeding rollers. 65

14. In a printing machine, the combina-

tion with a form or plate cylinder, a platen cylinder, means rotating said cylinders and an inking mechanism, of a wiping and polishing mechanism comprising a continuous strip of absorbent material a plurality of feeding rollers on one side of said cylinders, a guide roller between said feeding rollers and said cylinders and in close juxtaposition to said form or plate cylinder, a guide roller on the opposite side of said form or 70 plate cylinder and adjacent thereto, means whereby said guide rollers are given simultaneous lateral reciprocation, a pressure roller bearing on said guide roller adjacent to said form or plate cylinder and adapted to 75 reciprocate therewith, means retarding the rotation of said pressure roller, further guides arranged between said feeding rollers and said pressure roller, an endless band passing around or over said guide rollers 80 respectively and between said feeding rollers, a reel whereby a roll of wiping cloth is supported adjacent thereto, guides arranged between said reel and said pressure roller, a re-winding reel, means whereby said 85 last mentioned reel is frictionally driven, means whereby said reel is released from said driving means, guides arranged between said re-winding reel and said feeding rollers, a supplemental re-winding reel and 90 means whereby said last mentioned reel is frictionally driven. 95

15. In a printing machine, the combination with a form or plate cylinder, means continuously rotating same, an inking mechanism and means continuously wiping and polishing the plates on said cylinder, of a D-roll adapted to frictionally engage said cylinder or the plate or plates thereon, means whereby said D-roll is given a positive impulse to initiate each rotation thereof and cause such frictional engagement, means momentarily checking the movement of said D-roll when it disengages said cylinder or the plate or plates thereon, and means whereby a continuous web is fed between said D-roll and said plate or form cylinder. 110

16. In a printing machine, the combination with a form or plate cylinder, means rotating same, an inking mechanism and means wiping and polishing the plates on said cylinder, of a D-roll adapted to frictionally engage said cylinder or the plate or plates thereon, means whereby said D-roll is given a positive impulse to initiate each 115 rotation thereof and cause such frictional engagement, means whereby said last mentioned means may be rendered inoperative, means checking the movement of said D-roll when it disengages said cylinder or the 120 plate or plates thereon, and means whereby when said means giving the starting impulse to said D-roll are inoperative, said D-roll will be held stationary. 125

17. In a printing machine, the combina- 130

tion with a form or plate cylinder, means 5
rotating same, an inking mechanism, and
means wiping and polishing the plate on
said cylinder, of a D-roll adapted to fric-
tionally engage said cylinder or the plate
or plates thereon, means whereby said D-roll
is given a positive impulse to initiate each
rotation thereof and cause such frictional
engagement, a brake member adapted to act
10 on said D-roll, an electro-magnet, an arm-
ature, connections between said armature and
said brake member, an electrical circuit in-
cluding said magnet therein and a make and
break mechanism included in said circuit,
15 actuated through the rotation of said cyl-
inder whereby movement of said D-roll is
checked when it disengages the said cylinder
or the plate or plates thereon.

18. In a printing machine, the combina-
20 tion with a form or plate cylinder, means
rotating same, an inking mechanism and
means wiping and polishing the plate on
said cylinder, of a D-roll adapted to fric-
tionally engage said cylinder or the plate
25 or plates thereon, means whereby said D-
roll is given a positive impulse to initiate
each rotation thereof and cause such fric-
tional engagement, a brake band carried by
said D-roll, a rocking brake head, a brake
30 shoe carried thereby adapted to engage said
brake band, a lever arm pivoted thereto and
to the frame of the machine, a second lever
arm, an adjustment screw carried thereby
engaging said first mentioned arm, an
35 armature carried by said last mentioned
arm, an electro magnet, an electrical circuit
including said magnet therein and a make
and break mechanism included in said cir-
cuit, actuated through the rotation of said
40 cylinder whereby movement of said D-roll
is checked when it disengages the said cyl-
inder, or the plate or plates thereon.

19. In a printing machine, the combina-
45 tion with a form or plate cylinder, means
rotating same, an inking mechanism, and
means wiping and polishing the plate on
said cylinder, of a D-roll adapted to fric-
tionally engage said cylinder or the plate or
50 plates thereon, means whereby said D-roll
is given positive impulse to initiate each
rotation thereof and cause such frictional
engagement, means whereby said last men-
tioned means may be rendered inoperative,
55 a brake band carried by said D-roll, a rock-
ing brake head, a brake shoe thereon
adapted to engage said brake band, a lever
arm pivoted thereto, a second lever arm, an
adjustment screw carried thereby engaging
60 said first mentioned lever arm, an electro
magnet, an armature on said second arm,
two electrical circuits including said magnet
therein, a make and break mechanism act-
uated through the rotation of said cylinder
65 whereby movement of said D-roll is checked
when it disengages said cylinder or the plate

or plates thereon, and a second make and
break mechanism actuated by said means
rendering said means giving the initial im-
pulse to said D-roll inoperative whereby
said brake will be set while said D-roll is 70
stationary.

20. In a printing machine, the combina-
75 tion with a form or plate cylinder, a gear
thereon, means rotating said cylinder, an
inking mechanism and means wiping and
polishing the plate on said cylinder, of a
D-roll adapted to frictionally engage said
80 cylinder, or the plate or plates thereon, an
abutment on one end thereof, a gear loosely
mounted relative to and concentric with said
D-roll, a plunger pin carried by said gear
and adapted to engage said abutment, and
means whereby said pin may be projected
85 to give said D-roll an initial impulse and
cause such frictional engagement. 85

21. In a printing machine, the combina-
90 tion with a form cylinder, a gear thereon,
means rotating said cylinder, an inking
mechanism and means wiping and polish-
ing the plate on said cylinder, of a D-roll
adapted to frictionally engage said cylinder,
95 or the plate or plates thereon, an abutment
on one end thereof, a gear loosely mounted
relative to and concentric with said D-roll,
a plunger pin carried by said gear and
adapted to engage said abutment, and a
lever presenting a bevel to said pin and an
abrupt decline from said bevel, whereby said
pin will be projected only to give said
D-roll an initial impulse to cause such fric-
100 tional engagement. 100

22. In a printing machine, the combina-
105 tion with a form or plate cylinder, a gear
thereon, means rotating said cylinder, an
inking mechanism and means wiping and
polishing the plate on said cylinder, of a
D-roll adapted to frictionally engage said
cylinder, or the plate or plates thereon, a
110 beveled abutment on one end thereof, a gear
loosely mounted relative to and concentric
with said D-roll, a beveled plunger pin car-
ried by said gear and adapted to engage
said abutment, and means whereby said pin
may be projected to give said D-roll an ini-
tial impulse and cause such frictional en-
gagement. 115

23. In a printing machine, the combina-
120 tion with a form or plate cylinder, means
continuously rotating same, a D-roll adapted
to frictionally engage said cylinder or the
plate or plates thereon, means whereby said
D-roll is intermittently driven from said
cylinder, an inking mechanism and a wip-
ing and polishing mechanism, of means sup-
porting a paper roll, and means guiding a
125 continuous web arranged between said fast
mentioned means and said cylinder.

24. In a printing machine, the combina-
130 tion with a form or plate cylinder, means
continuously rotating same, a D-roll adapted

to frictionally engage said cylinder, or the plate or plates thereon, means whereby said D-roll is intermittently driven from said cylinder, an inking mechanism and a wiping and polishing mechanism, of means supporting a paper roll, means guiding a continuous web, arranged between said last mentioned means and said cylinder, a re-winding reel, means whereby said reel is frictionally driven, and guides between said cylinder and said reel.

25. In a printing machine, the combination with a form or plate cylinder, means continuously rotating same, a D-roll adapted to frictionally engage said cylinder, or the plate or plates thereon, means whereby said D-roll is intermittently driven from said cylinder, an inking mechanism and a wiping and polishing mechanism, of means supporting a paper roll, means guiding a continuous web, arranged between said last mentioned means and said cylinder, a re-winding reel, means whereby said reel is frictionally driven, guides between said cylinder and said reel, a reel for an insert web adjacent to said re-winding reel, and guides between said two reels.

26. In a printing machine, the combination with a form or plate cylinder, means 30 rotating same, an inking mechanism means wiping and polishing the plate on said cylinder, a D-roll adapted to frictionally engage said cylinder, or the plate or plates thereon, means whereby said D-roll is given 35 a positive impulse to initiate each rotation thereof and cause such frictional engagement, means whereby said last mentioned means may be rendered inoperative, and means whereby when said means giving the 40 starting impulse to said D-roll are inoperative, said D-roll will be held stationary, of a fountain, means whereby the liquid therein may be transferred to the surface of the paper, a reservoir, a pipe leading from said 45 reservoir to said fountain, an electrically operated valve therein, and a make and break mechanism actuated by said means

controlling the means giving the starting impulse to the D-roll whereby when said D-roll is stationary, said valve will be closed. 50

27. In a printing machine, the combination with a form or plate cylinder, a platen cylinder, means rotating said cylinders, an inking mechanism, a wiping and polishing mechanism and means whereby a continuous 55 paper web is fed between said cylinders of a heating mechanism disposed beyond said form or plate cylinder comprising a heated roller disposed above and beyond said platen cylinder, a plurality of resistance coils extending therefrom and a box inclosing and having a clear field above, said coils. 60

28. In a printing machine, the combination with a form or plate cylinder, a platen cylinder, means rotating said cylinders, an 65 inking mechanism, means whereby a continuous web is fed between said cylinders, a re-winding reel, and means whereby said reel is frictionally driven, of a heated roller disposed adjacent to said form or plate cylinder, a plurality of resistance coils extending therefrom to a point adjacent to said re-winding reel, and a box inclosing and having a clear field above, said coils. 70

29. In a printing machine, the combination with a form or plate cylinder, means continuously rotating same, a D-roll adapted to frictionally engage said cylinder or the plate or plates thereon, a blanket on said D-roll means whereby said D-roll is intermittently driven from said cylinder, an inking mechanism; a wiping and polishing mechanism and means automatically taking up slack in the blanket on said D-roll, of means supporting a paper roll, and means 80 guiding a continuous web arranged between said last mentioned means and said cylinder. 85

In witness whereof, I have hereunto affixed my signature, this fifth day of February 1907, in the presence of two witnesses.

WARREN L. GREEN.

Witnesses:

K. BAILEY,
C. L. LEE.
